UNITED STATES PATENT OFFICE.

WILBER E. HUNTER, OF MORGANTOWN, WEST VIRGINIA.

DESIGN FOR AN ARTICLE OF MANUFACTURE.

48,936.

Specification for Design.

Patented Apr. 25, 1916.

Application filed October 1, 1915. Serial No. 53,644. Term of patent 7 years.

To all whom it may concern:

Be it known that I, WILBER E. HUNTER, a citizen of the United States, residing at Morgantown, in the county of Monongalia and State of West Virginia, have invented a new, original, and ornamental Design to Be Applied to an Article of Manufacture, of which the following is a specification, reference being had to the accompanying drawing, forming a part thereof.

The figure is a perspective view of a goblet showing my new design.

By referring to the drawing, it will be seen that the design consists of a cartouche, with sides straight for a distance which are then curved inwardly and downwardly, the upper central portion of the cartouche being convex; the inner borders of the cartouche consisting of inwardly extending parallel lines. At the top of the cartouche there is a fleur-de-lis, at each side of which there is a foliated border which extends downwardly at the sides of the cartouche, chains of bells being curved downwardly and inwardly from the foliated border to a pendant. Above the pendant, and connecting the

curved lower sides of the cartouche there is a floral design. Within the cartouche there is a vase, at the top of which are a plurality of feathers, the vase having handles at its sides and there being a leaf-like design at the bottom of the vase. At each side of the cartouche there is a rosette, above each of which there is a flower, and below each of which there is a pendant.

My design may be stamped, printed, imprinted, embossed, or worked on or in, or cut upon or in, or executed by an etching process, pantograph, or by any other method on glassware, china, paper, cloth or any other fabric, or upon any metal, or any other suitable material, and may be produced on or in or attached to any desired article of manufacture.

I claim:

The ornamental design to be applied to an article of manufacture, as shown and described.

WILBER E. HUNTER.
